UNITED STATES PATENT OFFICE

LOWELL W. SHIELDS, OF ROCHESTER, NEW YORK, ASSIGNOR TO HICKOK MANUFACTURING COMPANY, INC., OF ROCHESTER, NEW YORK, A CORPORATION OF NEW YORK

DESIGN FOR SUSPENDERS

Application filed February 2, 1932. Serial No. 42,711. Term of patent 3½ years.

To all whom it may concern:

Be it known that I, LOWELL W. SHIELDS, a citizen of the United States, residing at Rochester, in the county of Monroe and State of New York, have invented a new, original, and ornamental Design for Suspenders, of which the following is a specification, reference being had to the accompanying drawings, forming part thereof.

In the drawings:

Figure 1 is a plan view of the front of the suspenders.

Fig. 2 is a fragmentary detail view of a portion of the rear of one of the suspender ends and a portion of the front strap.

Fig. 3 is a cross sectional view through one of the front straps.

The salient features of the design reside in the straps presenting on their front face, a body portion of one color and rounded longitudinal beads at the edges thereof and of a contrasting color, the beads at the rear face of the front straps being extended laterally to a greater extent than on the front.

I claim:

The ornamental design for suspenders, as shown and described.
